STORAGE CONTAINER

Bengt Anders Bjork, Eskilstuna, Sweden, assignor to
AB Nike Hydraulik, Eskilstuna, Sweden

Filed May 18, 1973, Ser. No. 361,785

Term of patent 14 years

Int. Cl. D9—03

U.S. Cl. D9—222

FIG. 1

FIG. 2

FIG. 5

FIG. 8

FIG. 10

FIG. 9

FIG.3

FIG.4

FIG.7

FIG.6

FIG.12

FIG.13

FIG.11

FIG.14

FIG. 1 is a perspective view of a storage container showing my new design;

FIG. 2 is a front elevational view with lid omitted;

FIG. 3 is a top plan view with lid in place;

FIG. 4 is a top plan view on an enlarged scale with the lid omitted;

FIG. 5 is a sectional view taken on the line 5—5 of FIG. 4 but on the same scale as in FIGS. 1, 2 and 3;

FIG. 6 is a rear elevational view with the lid in place but on the same scale as FIG. 4;

FIG. 7 is an elevational view looking from the left of FIG. 6.

FIG. 8 is a side elevational view of the lid on the same scale as in FIGS. 4, 6 and 7;

FIG. 9 is a front elevational view of the lid on the same scale as in FIG. 8;

FIG. 10 is a rear elevational view of the lid on the same scale as in FIGS. 8 and 9;

FIG. 11 is a bottom plan view on the same scale as FIG. 4;

FIG. 12 is a top perspective view without the lid on the same scale as FIG. 4;

FIG. 13 is a side elevational view on the same scale as FIG. 7 showing a modified form of my new design as with the lid omitted, the modified form being identical with the previously described form except for the specific handle portion; and

FIG. 14 is a top plan view of the modified form with the lid omitted.

I claim:

The ornamental design for a storage container, as shown and described.
